UNITED STATES PATENT OFFICE.

SWEN PAULSON, OF HEBER CITY, UTAH.

KNIFE.

1,252,486.

Specification of Letters Patent.

Patented Jan. 8, 1918.

Application filed January 19, 1917. Serial No. 143,330.

To all whom it may concern:

Be it known that I, SWEN PAULSON, a citizen of the United States, residing at Heber City, in the county of Wasatch and 5 State of Utah, have invented certain new and useful Improvements in Knives, of which the following is a specification, reference being had to the accompanying drawings.

10 This invention comprehends certain new and useful improvements in knives, and relates particularly to the type of knives commonly called jack knives, pen knives, or pocket knives, although it is to be understood that the invention is not limited in 15 this regard.

The invention has for its primary object a practical, durable and efficient construction of knife wherein the blade and handle are 20 so connected together that they may be securely held in extended relation to each other without any danger of the blade accidentally closing upon the fingers of the user, and whereby also, by the same construction, 25 and arrangement of parts, the blade will be securely held nested in the handle and all possibility of accidental opening will be positively precluded.

And the invention also aims to generally 30 improve devices of this kind so as to render them more useful and commercially desirable.

With these and other objects in view, as will more fully appear as the description 35 proceeds, the invention consists in certain constructions, arrangements and combinations of the parts that I shall hereinafter more fully describe and claim.

For a full understanding of the invention, 40 reference is to be had to the following description and accompanying drawing, in which—

Figure 1 is a side elevation of a knife embodying the improvements of my invention, 45 the blade being closed.

Fig. 2 is a similar view with the blade open and with the latch member turned out at an angle to the handle.

Fig. 3 is an edge view with parts in section.

Fig. 4 is a transverse sectional view on the line 4—4 of Fig. 3.

Figs. 5, 6 and 7 are fragmentary sectional side elevations illustrating the operation of the device.

Corresponding and like parts are referred to in the accompanying drawing and following description by like reference characters.

Referring to the drawing, the numeral 1 designates the blade of my improved knife 60 and 2 the handle thereof as a whole. The handle 2 embodies two side plates or bars 3, preferably formed of metal and connected together in a yielding manner. In the present embodiment of the invention, although 65 it is to be understood that the invention is not limited in this regard, the bars 3 are longitudinally channeled, as indicated at 14, and are formed of a single strip of spring steel doubled upon itself to form a connecting 70 member 5, this construction and arrangement of parts permitting one of the side bars 3 to be pressed, by the hand of the user of the knife, toward the other bar, for a purpose hereinafter described. The blade 1 is 75 formed with a shank 6 which is substantially square, as shown, whereby it may be securely held in between the channels 4 of the bars when they are pressed toward each other. 7 designates a pivot pin for the blades, said 80 pin being preferably riveted or otherwise rigidly secured at one end to one of the side bars 3 of the handle and extending at its other end through an aperture 8 formed in the other side bar, said pin being formed 85 at this end with a transversely extending head 9.

It is to be understood that the shank 6 of the blade 1 is apertured to receive the pin 7 whereby the blade is pivotally mounted 90 thereon and connected to the handle, and also pivotally mounted upon the pin 7 on the outer face of the apertured side bar 3 a swinging latch member 10 is mounted, said 95 latch member being formed in its outer face with a transversely extending recess 11 designed to receive the transversely extending head of the pin 7 when the latch member is turned out into angular relation to the handle whereby in this position of the parts, 100 the side bars 3 will be permitted by their spring action to move laterally one from the other, and release the head 6 so that the blade 1 may be turned either to an open or closed position. It will now be understood that 105 upon turning the latch member 10 to a position in alignment with the handle, as best illustrated in Fig. 3, the jaws formed by the ends of the channeled side bars 3, will close 110 upon the shank 6 of the blade 1 and securely

hold the blade in either a fully opened or closed position. Preferably the latch member 10 is formed on its outer face with one or more longitudinal recesses 12 to engage 5 with the head 9 when the latch member is in its operative position lying in alignment with the handle; and preferably one end of said latch member is inclined as indicated at 13, to engage with the correspondingly 10 formed end 14 of one of the cheek pieces or panels 15 secured in the usual manner to the side bars 3, whereby the movement of the latch member 10 will be limited in one direction. It is also preferred that the recess 11 15 be inclined on its opposite side walls, as indicated at 11', whereby the movement of the latch member from its inoperative position in angular relation to the handle in a direction to properly close the latch member 20 against the handle will be facilitated, as the head 9 will easily ride upon these inclined surfaces 11'.

From the foregoing description in connection with the accompanying drawing, the 25 operation of my improved knife will be apparent. In the practical use of the device, when the blade is in closed position, it will be received within the channels 9 of the side bars 3, and the latch member 10 will lie in 30 longitudinal alignment against the outer face of one of the side bars whereby the jaws formed at the ends of the channeled bars 3 will securely embrace the blade shank 6 between them and effectually prevent any 35 accidental opening of the knife. In order to open the knife it is only necessary for the user to swing the latch member 10 outwardly into an angular position relative to the handle whereupon the head 9 of the pin 7 will 40 move into the recess 11 and the side bars 3 will automatically spring away from each other, and the shank 6 will be released so that the blade may be turned upon the pivot pin 7 to full open position, whereupon the 45 latch member 10 is returned to the position shown in Fig. 1, the inclined sides of the member 11' of the recess 11' wedging upward upon the head 9 and causing the jaws formed at the ends of the channel members 50 3 to again securely embrace the blade shank 6 and hold the blade open.

While the accompanying drawing illustrates what I believe to be the preferred embodiment of my invention, it is to be understood that the invention is not limited thereto, but that various changes may be made in the construction, arrangements and proportions of the parts without departing from the scope of the invention as defined in the 55 appended claims.

What is claimed is:

1. A knife comprising a handle including side bars resiliently urged away from each other, a blade, a pivot pin upon which the 60 blade is mounted passing through said side

bars and having a head, and a latch member engaging between said head and one of the side bars and when turned in one position having wedging engagement with the head to urge the side bars toward each other and in another position permitting the side bars to spring away from each other to thereby release the grip of the side bars upon the blade and permit the blade to be shifted. 70

2. A knife of the character described, 75 comprising a blade embodying channeled side bars yieldingly connected together, a pivot pin carried by said side bars and on which the blade is pivotally mounted, said pin being formed at one end with a head, 80 and a swinging latch member rotatably mounted upon said pin back of the head and designed for wedging engagement therewith whereby to hold the side bars clamped upon the blade. 85

3. As a new article of manufacture, the herein-described knife, comprising a blade, a handle embodying channeled side bars and a connecting member yieldingly joining said 90 bars together at one end, a pivot pin connected at one end to one of the side bars, and passing freely through the other one, the blade being pivotally mounted on said pin, and the pin being formed at one end with a head, and a swinging latch member mounted 95 upon said pin back of the head and formed with a recess to receive the head, said recess having an inclined side wall for the purpose specified.

4. As a new article of manufacture, the 100 herein described knife, comprising a blade, a handle embodying channeled side bars and a connecting member yieldingly joining said side bars together at one end but resiliently urging said side bars apart, a pivot pin connected at one end to one of the side bars and passing freely through the other one, the 105 blade being pivotally mounted on said pin, and the pin being formed at one end with a head, and a swinging latch member mounted 110 upon said pin back of the head and formed with a recess to receive the latter, and with an inclined end, the handle being formed with a cheek piece adapted to engage the end 115 of said latch member to limit the swinging movement thereof in one direction.

5. As a new article of manufacture, a 120 knife comprising a blade having a shank, a handle comprising channeled side bars connected to each other by an integral resilient member urging the side bars apart, a pivot pin connected at one end to one of the side bars and passing freely through the other side bar, on which pin the blade is pivotally mounted, said pin being formed on one end 125 with a head, and a swinging latch member mounted upon the pin inward of the head and bearing flat against one of the side bars, said latch member having a transversely extending recess intersecting the opening for 130

the pivot pin, said recess, when the latch is shifted into a position at right angles to the handle, receiving the head of said pin and permitting the side bars to move away from each other to thereby release the knife from its engagement by the jaws formed on said side bars, said latch when turned into a position parallel to the handle engaging the head

to draw the side bars toward each other and grip the shank of the knife.

In testimony whereof I hereunto affix my signature in the presence of two witnesses.

SWEN PAULSON.
